CLAIM

The ornamental design for a child safety seat, as shown and described.

DESCRIPTION

FIG. 1 is a top, front, right side perspective view of a child safety seat wherein the support anchor is in a retracted position showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a top, front, right side perspective view of the child safety seat in FIG. 1 wherein the support anchor is in an extended position;

FIG. 8 is a front elevation view thereof;

FIG. 9 is a rear elevation view thereof;

FIG. 10 is a left side elevation view thereof;

FIG. 11 is a right side elevation view thereof; and,

FIG. 12 is a top plan view thereof.

The broken lines depict portions of child safety seat that form no part of the claimed design.
